UNITED STATES PATENT OFFICE.

ELMER J. TSCHANTZ, OF CANTON, OHIO.

DESIGN FOR A BAKING-IRON.

58,050.

Specification for Design.

Patented May 31, 1921.

Application filed December 16, 1920. Serial No. 431,267. Term of patent 7 years.

To all whom it may concern:

Be it known that I, ELMER J. TSCHANTZ, a citizen of the United States, residing at Canton, in the county of Stark and State of Ohio, have invented a new, original, and ornamental Design for a Baking-Iron, of which the following is a specification, reference being had to the accompanying drawing, forming part hereof.

Figure 1 is a plan view of a baking iron, showing my new design; and Fig. 2, a side elevation of the same.

I claim:

The ornamental design for a baking iron, as shown.

ELMER J. TSCHANTZ.
